UNITED STATES PATENT OFFICE.

DANIEL B. COATES, OF PAYETTE, IDAHO.

CATTLE-STANCHION.

1,397,833.

Specification of Letters Patent.

Patented Nov. 22, 1921.

Application filed June 20, 1921. Serial No. 478,899.

To all whom it may concern:

Be it known that I, DANIEL B. COATES, a citizen of the United States, and a resident of Payette, in the county of Payette and State of Idaho, have invented certain new and useful Improvements in Cattle-Stanchions, of which the following is a specification.

My invention relates to cattle stanchions, and a purpose of my invention is the provision of a stanchion of extremely simple, durable and inexpensive construction having a locking lever permanently carried by the stanchion and operable to automatically 15 lock the stanchion in contracted position.

I will describe only one form of stanchion embodying my invention and will then point out the novel features thereof in claims.

In the accompanying drawings:

20 Figure 1 is a view showing in perspective one form of stanchion embodying my invention.

Fig. 2 is a fragmentary sectional view of the stanchion shown in Fig. 1 in contracted 25 or locked position.

Fig. 3 is a fragmentary view showing the stanchion in side elevation and in expanded or released position.

Fig. 4 is a fragmentary view showing the 30 stanchion in end elevation with the locking lever in section to disclose the contour of the locking pawl.

Fig. 5 is a view similar to Fig. 4 with the locking link and lever in locking position.

35 Similar reference characters refer to similar parts in each of the several views.

Referring specifically to the drawings and particularly to Fig. 1, my invention in its present embodiment comprises side bars B and B' formed of wood or any other suitable 40 material, and end bars E and E' each of which latter is formed of strap irons 15 and 15^a or 16 and 16^a, respectively, having angularly disposed end portions 17 which are secured to the opposite ends of the bar B' by 45 means of bolts 18 so that they are rigidly supported in right angular position with respect to the bar. The bar B' may be considered a stationary bar while the bar B is

50 a movable bar to permit of the application and removal of the stanchion to or from an animal. The bar B is mounted for swinging movement upon a bolt 19 extending through the strap irons 15 and 15^a and through the 55 adjacent end of the bar B. The opposite end of the bar B is provided with a cap iron

or yoke 20 secured thereto by means of a bolt 21 in the manner clearly shown in Fig. 2. As shown in this latter figure, the iron 20 and the bar B are formed with registering openings, with the outer opening of the cap iron provided with a tangentially arranged slot 22.

The bar B is adapted to be locked in the position shown in Figs. 1 and 2 by means of a locking link L and a locking lever V. As illustrated to advantage in Figs. 2 and 3, the link L is pivoted at one end upon a bolt 23 spanning the strap irons 16 and 16^a, and this link is of circular form in cross section 70 for a major portion of its length with that end connected to the locking lever V flattened as indicated at 24 so as to removably fit within the tangential slot 22. The locking lever V is connected to the flat end of the 75 link L by means of a pin 25 so as to occupy a substantially horizontal position as shown in Fig. 3 or a vertical position as shown in Fig. 2. This lever V is formed at its upper end with a lug 26 provided for the purpose 80 of raising the link out of the opening of the cap iron when moving the link and lever to released position. The lower end of the lever is bent upon itself to provide a retaining eye 27 which is of such a size as to prevent its passage through the openings of the bar B and the cap iron 20 in the manner clearly shown in Fig. 3 and to thus prevent the complete disengagement of the lever 85 with respect to the bar B. In the applied position of the stanchion, it is suspended from a suitable beam (not shown) overlying the manger by means of an eye bolt 28 swivelly connected to the strap irons 16 and 16^a through the medium of a bolt 29. The 90 lower end of the stanchion is movably associated with the floor of the manger by means of a chain 30 connected to a bolt 31 spanning the strap irons 15 and 15^a. By this arrangement it will be seen that the 95 stanchion is supported for universal movement so as to conform to the movements of the animal.

In practice, the stanchion is applied to the neck of an animal by moving the bar B to 105 expanded or released position, and to this end it is necessary to lift the locking lever V from the position shown in Fig. 2 to that shown in Fig. 3 whereby the lock 26 operates to lift the flat end 24 of the link L from the tangential slot 22 thereby permitting of 110 the outward swinging movement of the bar

to the position shown in Fig. 3. After the stanchion has been applied to the neck of the animal, the bar B is moved to contracted position whereupon the link L is dropped into the tangential slot 22 and the lever to vertical position. This operation of the locking means is automatic as when the bar B is moved to contracted position the link L automatically falls into the slot 22 and the lever V gravitates to vertical position. This effects a secure locking of the stanchion in applied position upon the neck of an animal.

Although I have herein shown and described only one form of stanchion embodying my invention, it is to be understood that various changes and modifications may be made herein without departing from the spirit of the invention or the spirit and scope of the appended claims.

20 What I claim is:—

1. A cattle stanchion comprising end members, a side member rigidly connecting the end members, and a second side member pivotally connected to one of the end members to occupy contracted and expanded positions, and means for locking the side member in contracted position comprising a link movable through the side member and pivotally connected to the end member, said link being provided with a flattened portion and said side member with a slot for receiving the flat portion, and a locking lever pivotally connected to the link at the flat portion and operating to retain the link within the slot and to effect the removal thereof when lifted.

2. A cattle stanchion comprising end members, a side member rigidly connecting the end members, and a second side member pivotally connected to one of the end members to occupy contracted and expanded positions, and means for locking the side member in contracted position comprising a link pivotally connected to the end member and having a flat portion, said pivoted side member being formed with a slot to receive the flat portion, and a lever pivotally connected to the link, a lug formed on the lever adapted to remove the link from the slot when said lever is moved, and an eye formed on

the other end of the lever for permanently retaining the lever against removal from the side member.

3. A stanchion comprising end members composed of strap irons arranged in parallelism, a side member rigidly connecting the end members, a second side member pivotally connected between the irons of one end member and adapted to occupy a contracted position wherein the other end is disposed between the angle irons of the other end member, a cap iron on the free end of the second side member, registering openings formed on the second side member and cap iron, a slot communicating with one of the openings and cap iron, a link pivotally connected to the strap irons of the second named member, said link being arranged for movement through the openings of the cap iron and side member and having a flat portion adapted to repose in said slot, a lever pivotally connected to said link, a lug formed on the lever and adapted to engage the wall of one of said openings to effect removal of the link from said slot, and an enlarged portion formed on the opposite end of the lever for maintaining the lever against removal from the side member and cap iron.

4. A cattle stanchion comprising end members, a side member rigidly connecting the end members, a chain connected to one of the end members, an eye bolt universally connected to the other end member, a second side member pivotally connected to one of the end members, a cap iron mounted on the free end of the second side member, registering openings formed in the second side member and said cap iron with one of the openings of the cap iron communicating with a slot, a link pivotally connected to one of the end members, said link being movable through the openings of said side member and cap iron and having a flat portion adapted to repose in said slot, and a locking lever pivotally connected to said link at the flat portion and operable to retain the link within said slot when in one position and to effect removal thereof when moved to another position.

DANIEL B. COATES.
